UNITED STATES PATENT OFFICE

ELWIN H. KIDDER, OF CHICAGO, ILLINOIS, ASSIGNOR TO LINK-BELT COMPANY, OF CHICAGO, ILLINOIS, A CORPORATION OF ILLINOIS

GRAIN DEFLECTOR

Application filed November 25, 1929. Serial No. 409,497.

My invention relates to a power operated grain deflector, and is particularly applicable for use with a grain car unloader of the type in which a side door grain car is tilted both laterally and longitudinally in order to deliver through the side door the grain contained within the car. One object of my invention is to provide a grain deflector which may be inserted through the side door into the car during the tilting operation, in order to deflect from the car grain which would otherwise not escape through the door. Another object is the provision of such a deflector as may be power operated and controlled with a minimum of labor and supervision. Another object is the provision of such a deflector which will occupy a minimum of space when out of use, and which, for example, may be folded along the side of the car and its supporting cradle, when withdrawn from the car. Another object is the provision of such a deflector as will automatically fold into horizontal alignment with the car, when it is withdrawn from the car. Another object is the provision of means for withdrawing said deflector initially along the plane of the car bottom, during the beginning of its withdrawal, and for lifting it upwardly away from the bottom of the car after a predetermined portion of its excursion of withdrawal has been completed. Another object is the provision of a system of weights and counterweights which is operated, in association with actuating motor means, for effecting the lifting of the deflector at a predetermined point in its movement. Another object is the provision of improved guiding means for such a deflector, during its insertion into and its withdrawal from the car. Other objects will appear from time to time in the course of the specification and claims.

I illustrate my invention more or less diagrammatically in the accompanying drawings, wherein—

Figure 1 is a side elevation with parts in section;

Figure 2 is an end elevation;

Figure 3 is a partial diagrammatic view on a larger scale, with parts broken away and some in section, illustrating the deflector

member and the supporting and actuating structure therefor;

Figure 4 is a section on the line 4—4 of Fig. 3;

Figure 5 is a section along the line 5—5 of Fig. 3;

Figure 6 is a partial plan view illustrating the deflector inserted in working position within the car;

Figure 7 is an enlarged plan view illustrating the deflector in withdrawn position;

Figure 8 is a section on an enlarged scale along the line 8—8 of Fig. 3;

Figure 9 is a section through the car, illustrating the deflector in operative position;

Figure 10 is a section on the line 10—10 of Fig. 9, and

Figure 11 is a section on the line 11—11 of Fig. 9.

Like parts are indicated by like symbols throughout the specification and drawings.

Considering first the general showing of Figs. 1 and 2, I illustrate more or less diagrammatically a car unloader structure, the details of which do not of themselves form part of the present invention, but must be to some extent shown in order to illustrate the application of the present invention. A car support or cradle, generally indicated as A, is provided with the arcuate tilting support A¹ resting, for example, upon rollers A². A³ indicates a cable anchored at either end, as at A⁴, to the opposite ends of the arcuate member A¹. The cable A³ passes about any suitable drum A⁵, which may be driven through the gear reduction A⁶ by any suitable motor means A⁷.

It will be understood that through the actuation of the motor A⁷ the car support may be tilted about a transverse axis to impart to car B an endwise tilting movement. The car may be positioned upon the tracks B¹ and may be held in position thereupon during this tilting movement by any suitable clamps B², the details of which need not be considered, it being understood that the clamps may be removed out of line of the car to permit the car to pass from the supporting tracks B¹ to the fixed tracks B³.

In addition to the endwise tilting of the

support A, means are provided for tilting it transversely. I illustrate, for example, a downward extension C with the gear segment C¹ in mesh with the pinion C², which 5 may be driven through the gear C³ and the pinion C⁴ and any suitable power, for example a motor C⁵. It will be seen that the transverse tipping excursions is through a substantially smaller arc than the endwise 10 tipping excursion; an arc of 15 degrees is ordinarily sufficient. It will be understood, of course, that the support A, with the depending portion C, is tilted laterally in relation to the cradle as a whole, and in particular is tilted laterally in relation to the arcuate members A¹. In operation the lateral tilting takes place first and then the supporting structure as a whole is longitudinally tilted.

Grain doors are ordinarily provided with 20 wooden inner doors within the normally sliding doors of the car. These inner doors may merely be boards nailed in the car from within, or unitary board structures. In any case they may be removed by an outward pressure 25 against them, after the permanent sliding door of the grain car has been moved out of alignment with the car door. I illustrate, as a means for removing these doors, a structure which may be moved into contact 30 with the inner door when the car is in the upright position in which it is shown in Fig. 2. The lateral tilting of the car moves the car against this fixed means and gets the result of thrusting the grain door inwardly 35 against the grain, although it is the part which is moved while the door remains stationary. I illustrate as means for effecting this result the door moving member D, which is mounted upon an arm or supporting structure D¹, which may be positioned in proper 40 position in relation to any given car and door, as by the connecting arm D², which may be set by means of a segment D³ with its ratchet teeth D⁴, which may be held as by the pawl D⁵ to prevent retrograde movement of the 45 segment. The segment may be moved forwardly, as through the bevel gear D⁶, the pinion D⁷ and the manually operable handle D⁸. The details of this car-opening mechanism form no part of the present invention 50 and are herein summarily indicated and described merely to make clear the whole operation of removing the grain from the car. It will be understood that when the member D is placed in proper position against the grain door, the car is tilted laterally, as by rotation of the gear C³. When the car has 55 been tilted laterally and the door removed, the grain will pour out into any suitable receiving hoppers or means not herein shown, being received first upon any suitable chute or incline D¹⁰. Any suitable means may be employed, for example the cable D¹¹ passing about the sheaves D¹², for lifting the door 60 removing member D out of the line of flow of

the grain and out of the path of movement of the deflector. The final position of the member D is illustrated, for example, in Fig. 9, with the car tilted and the grain door D¹⁴, upon the member D, positioned upwardly 70 out of line with the deflector member.

Assuming that the car has been transversely tilted and the door has been removed in the position in which it is shown in Fig. 9, and that the car support as a whole has been longitudinally tilted one or more times, to cause the escape of a substantial proportion of the grain, then the deflector structure is employed, the deflector proper being thrust transversely across the car floor, at an angle, to deflect outwardly through the car door opening the remaining grain, as the car is again longitudinally tilted. This provides a means for disposing of the grain which collects in the corner of the car, and which would not normally escape from the car in response to the ordinary tilting operation above described.

The deflecting structure is generally shown in Fig. 3, wherein is illustrated the deflector blade E, which is shown as higher at its inner than at its outer end. It is overhung along its upper edge as at E¹, and may be provided along its lower edge with any suitable bottom member E², of belting or the like, which serves to protect both the deflector member itself and the bottom of the car from battering, and which tends to make easier the sliding of the deflector across the bottom of the car. It also tends, through its flexibility, to make a tighter, cleaner connection with the floor.

G generally indicates the deflector-actuating arm secured at one end of the vertical shaft K and held against rotation in relation thereto. The arm, which is shown in section in Fig. 8, may be formed of the channel members G² connected by side plates G³. Pivoted to the arm at its opposite end, as at G⁴, is the guiding or lifting block G⁵, on which are mounted the three sheaves G⁶. Pivoted in turn to the block G⁵, as at G⁷, for rotation about a generally horizontal axis, is the guiding and supporting arm generally indicated as G⁸. The arm is pivoted at its opposite end, as at G⁹, to the deflector member E. The arm G⁸, as shown in section in Fig. 10, may be formed of two angle members G¹⁰ G¹¹, in position on opposite sides of the deflector member E and spaced therefrom by any suitable spacers G¹². In order to permit rotation of the member E about the pivot G⁹, it is provided with an arcuate slot G¹³, in line with which are the spacers G¹⁴ through which pass the bolts G¹⁵ which tie the structure together. G¹⁶ is a plate which is proportioned to mask the arcuate aperture G¹³, to prevent the escape of grain therethrough. The plate is fixed in relation to the arm but is so proportioned as to cover the aperture G¹³ when the 110 115 120 125 130

deflector member is in operative position. The rotation of the arm G^8 in relation to the block G^5 is limited, for example by the upper and lower stops G^{17} . Rotation of the deflector E in relation to the arm G^8 is limited, in the first place, by the relation of the blocks G^{14} to the arcuate slot G^{18} , and in the second place by the stop G^{18} upon the deflector E , which engages the lower side of the member G^8 when the deflector is lifted free from the floor, in response to the tilting of the deflector about the pivot G^9 , by gravity.

H generally indicates a connecting link which is provided with an adjustment, as at H¹. It is pivoted at one end, as at H², to the block G⁵. At the other end it is pivoted, as at H³, to the sliding shoe H⁴, which is mounted to slide longitudinally along the arm G. This structure is shown in section, for example, in Fig. 8. The shoe H⁴ may be guided, for example by the lower, outer angle members H⁵ and the upper, inner angle members H⁶. The inwardly turned flanges of these angles form a track beneath the arm G, along which track the shoe H⁴ may slide as the arm G rotates. Referring to Figure 7 the sliding shoe H⁴ is indicated in dotted line and, in the position in which the parts are there extends from the right of the cam roller H⁷ to the left of the cam roller H⁸.

On the lower side of the shoe H^4 are positioned two cam rollers. As shown in Figure 6, the first of these, H^7 , is in line with the generally arcuate outer cam slot H^8 . The second roller, H^9 , is in line with the more or less irregularly curved inner cam slot or track H^{10} . These cam members are mounted upon any suitable platform, positioned, as at H^{11} , on the edge of the cradle, which platform tilts longitudinally with the members A^1 .

45 Mounted upon the top of the arm G are a plurality of sheaves I I'. Of these, the sheave I is tangent to the central axis of the hollow shaft K and the sheave I' is closely adjacent the sheave I.

The shaft K is mounted for rotation about a vertical axis, passing downwardly through the platform H¹², it being mounted in any suitable bearings K¹ K². It has mounted on its lower end the bevel gear K³, which is in mesh with the bevel pinion K⁴ upon the shaft K⁵. At the opposite end of the shaft K⁵ is a bevel gear K⁶ in mesh with the bevel pinion K⁷ on the shaft K⁸. K⁹ indicates any suitable gear reduction and K¹⁰ any suitable power source, for example a motor. K¹¹ is any suitable solenoid brake for controlling the actuation of the motor.

60 Mounted on the shaft K⁸ is the drum L¹. Dead-ended on the drum L is the cable L¹, which passes about a sheave L², fixed on the frame of the cradle, and about the sheave L³, fixed on the guides L⁴, along which moves the large weight L⁵. It will be understood that the guides L⁴ are fixed to the cradle frame.

The cable continues about the sheave L^6 and downwardly through the large weight L^5 , terminating in a small weight L^7 . In the initial position of the device, the weight L^7 hangs somewhat below the bottom of the weight L^5 , 70 as shown in Fig. 3. The weight L^5 rests upon stops or angles L^8 , as shown in Figs. 3 and 5. The sheave L^6 is suspended at one end of a second cable M , which cable passes about the fixed sheaves $M^1 M^2 M^3 M^4$ and M^6, M^5 being tangential to the central axis of the shaft K . 75 The cable end passes upwardly through the center of the hollow shaft K and thence about the sheaves I and I^1 , along the length of the arm G , and about the sheaves G^6 , to be dead-ended finally upon the arm G^8 as at M^6 . 80

It will be realized that whereas I have described and shown a practical and operative device, nevertheless many changes might be made in size, shape, number, disposition and relation of parts without departing from the spirit of my invention. I therefore wish my drawings to be taken as in a broad sense illustrative and diagrammatic, rather than as limiting me to my precise disclosure.

The use and operation of my invention are as follows:

My deflector is particularly adapted for use in unloading grain from freight box cars which are first tilted laterally, to free the inner car door from the door frame, and are then tilted longitudinally to cause the grain to flow out through the side door of the car. However, I do not wish to be limited to the use of my device with any particular type of car, as it may be used with a variety of cars. In the use of such a device the member D is first advanced to position against the inner door, as shown in Figure 2. The car is then tilted laterally and the member D with the door upon it takes the position in which they are shown in Fig. 9. The motor A⁷ is then actuated to tilt the cradle and the car longitudinally. After the initial escape of the grain, and in order to clear from the car such grain as remains, for example such grain as gathers in the corners of the car, I insert, at an angle across the floor of the car, the deflector member E. It is important that this member be 115

It is important that this member be inserted angularly across the car, as shown for example in Fig. 6. Assuming that the deflector is in initial position folded up as shown in Figs. 1 and 7, I actuate the motor K^{10} to rotate the shaft K , and thereby to move the arm G in a clockwise direction, considering the parts in the position in which they are shown in Figs. 6 or 7. As the arm G rotates into the full line position in which it is shown in Fig. 6, the roller H^9 first engages the cam track H^{10} and moves the shoe H inwardly along the arm G . Shortly before the roller H^9 escapes the track H^{10} , the second roller H^7 engages the outer cam track H^8 . The effect of this combined cam action is to move 120 125 130

the shoe H^4 inwardly along the arm G and to rotate the block G^5 , and with it the deflector member E , into the final or operative position in which they are shown in full line 5 in Fig. 6. When the parts are in the initial position in which they are shown in Fig. 7, the counterweight L^5 is at the upward limit of its movement, with the smaller weight L^7 engaging the bottom of the weight L^5 , 10 since it is through the weight L^7 and the cable L^1 that the larger weight is held in its uppermost position. As the parts rotate to the final position, the cable L^1 is paid out by the drum L and permits the weight L^5 to 15 drop to its lowest position against the stop L^8 . The large weight reaches this position at the time when the deflector is in the dotted line position in Fig. 9. Referring to the lower right-hand corner of the deflector as 20 shown in Fig. 9, the dotted line X indicates the path of this corner after the large weight ends its excursion. The lateral movement of the end of the arm G continues, the deflector being thrust further into the car, but the deflector itself, and the arm G^8 , overcome the 25 weight of the small weight L^7 , and therefore the deflector is able to sink downwardly into contact with the floor of the car, and to slide forwardly along the floor of the car, until 30 the final position is reached. When the deflector actually reaches the floor of the car and rests against it, the proportion of the parts is such that the weight L^7 still has a little slack and can pull the cable L^1 down 35 sufficiently so that the weight hangs clear of and somewhat below the bottom of the large weight L^5 . This serves to keep the cable taut. When the movement of the deflector has been completed and it is thrust as far 40 into the car as is necessary, the car is tilted longitudinally and the grain flows against the forward overhanging face of the deflector and flows outwardly there-along to escape 45 to the receiving bins, conveyors or the like.

It will be observed, as from Fig. 9, that by moving or tilting the deflector downwardly before thrusting it to the limit of its excursion into the car, the member D and the door D^{14} are cleared by the deflector, which passes 50 easily beneath them. The overhanging portion E^1 of the deflector serves to check any tendency of the grain to flow over the upper edge of the deflector.

After the tilting operation is completed, 55 the deflector is removed by again initiating rotation of the motor K^{10} . The shaft K is rotated in a reverse direction and, as the arm G begins its counter-clockwise rotation, the deflector E slides outwardly along the car 60 floor until the weight L^7 engages the bottom of the big weight. As it does so, the big weight overcomes the resistance by gravity of the deflector itself and the deflector tilts upwardly until the stop G^{18} engages the bottom of the arm G^8 . At this time the deflector

has taken the dotted line position as shown in Fig. 9. When the stop G^{18} engages the bottom of the arm G^8 , the arm has rotated upwardly until it engages the upper stop G^{17} . This termination of the movement of the deflector E and the arm G^8 in relation to the arm G causes the beginning of the upward movement of the weight L^5 , which is accordingly reeled in by rotation of the drum L . Thereafter the deflector E maintains a constant relationship to the block G^5 and the block and deflector, as a unit, are folded or jack-knifed against the arm G through the action of the link H , until the device reaches its initial position. Meanwhile the cable L^1 70 draws in on the weight L^5 , raising it to its uppermost position. 75

As a matter of convenience in operation, I provide a stationary platform shown in Fig. 2 and generally indicated as O . Upon it may be any suitable electrical controlling means O^1 , whereby the various motors may be actuated. 80

Among the characteristic features and advantages of my invention are the following. 85 The deflector may be compactly folded up along the side of the cradle and requires small side clearance for its operation when inserted in the car. This permits the use of a wide, undisturbed operator's platform close to the 90 side of the car. The deflector is inserted into and removed from the car, so far as the operator is concerned, by a single movement of the handle of the controller in either forward or reverse direction. Although the electrical 95 controls do not of themselves form part of the present device, it will be understood that the operation is interlocked electrically, so that the deflector cannot be inserted except when the cradle of the unloader is horizontal, 100 or when the end to which the deflector is attached is raised above its normal position. Owing to the necessity of maintaining the parts in a restricted space, the employment of two cam tracks is advantageous, the second 105 track, farther from the center of rotation of the deflector than the first, taking up the guiding operation at the extremity of the camming movement in relation to the first track. Since the deflector slides along the floor of 110 the car at a time when the floor is inclined to a position downwardly below the level of the control platform and the level of the plane of the car tracks when the car is in its initial horizontal position, it is necessary to lift the 115 deflector to clear the normal top of the cradle. It is for this purpose that the cable systems are used and the extent of the movement of the small weight before it contacts the large 120 counterweight determines the point at which the lifting of the deflector takes place. 125

I claim:

1. For use with a car unloader including a tiltable cradle and means for securing a car thereupon, a deflector member associated 130

with said cradle and means for inserting said deflector into and retracting it from the side door of said car, including a generally vertical shaft and means for rotating it, an arm extending generally horizontally therefrom, the deflector member being pivoted upon said arm.

2. For use with a car unloader including a tilttable cradle and means for securing a car thereupon, a deflector member associated with said cradle and means for inserting said deflector into and retracting it from the side door of said car, including a generally vertical shaft and means for rotating it, an arm extending generally horizontally therefrom, the deflector member being pivoted upon said arm, and means for rotating said deflector member about its pivot, in response to rotation of said arm and shaft.
- 10 3. The structure of claim 2 characterized by the employment of a member slidably mounted along said arm, a linkage connecting said slidable member with the deflector member and means for moving said slidable member along said arm in response to rotation of the arm.

4. For use with a car unloader including a tilttable cradle and means for positioning a car thereupon, a deflector member associated with said cradle and normally positioned adjacent the side of said car and generally parallel with it, and means for moving said deflector member, from said parallel position, into and out of the car, characterized by the employment of an arm to which the deflector member is pivoted, means for rotating the arm about a generally vertical axis and means for rotating said deflector member about its pivotal connection with the arm, in response to rotation of the arm.

5. For use with a car unloader including a longitudinally tilttable cradle and a car support laterally tilttable in relation to said cradle, and means for securing a car thereupon, a deflector member associated with the longitudinally tilttable cradle, and means for inserting it into and retracting it from the car, and means for permitting the lower edge of the deflector member to conform to the floor level of the laterally tilted car, when the deflector is in operative position, and for lifting said deflector upwardly from the car floor, at a predetermined point in its excursion of retraction from the car and for positioning its lower edge, when lifted, in a generally horizontal plane, at an angle to the plane of the tilted car floor.

6. For use with a car unloader including a longitudinally tilttable cradle and a car support laterally tilttable in relation to said cradle, and means for securing a car thereupon, a deflector member associated with the longitudinally tilttable cradle, means for inserting the deflector member into and reTRACTING it from the car and means for lift-

ing said deflector member from the floor of the car during the retracting excursion of the deflector, including a cable associated with the deflector and means, responsive to the movement of the deflector retracting means, for drawing in upon said cable.

7. For use with a car unloader including a longitudinally tilttable cradle and a car support laterally tilttable in relation to said cradle, and means for positioning a car thereupon, a deflector member associated with the longitudinally tilttable cradle, and means for inserting it into and retracting it from the car, including an arm upon which said deflector member is pivoted, a shaft to which said arm is fixed and means for rotating said shaft.

8. The structure of claim 7 characterized by the employment of means for lifting the deflector member from the floor of the car, during the retracting excursion of the deflector, said means including a cable associated with said deflector and extending downwardly through said shaft, and means for drawing in upon said cable during the retracting rotation of said shaft.

9. For use with a car unloader including a longitudinally tilttable cradle and a car support laterally tilttable in relation to said cradle, and means for positioning a car thereupon, a deflector member associated with the longitudinally tilttable cradle, and means for inserting it into and retracting it from the car, including a generally horizontal arm, means for rotating it about a generally vertical pivot, a block pivoted to the end of said arm, and a link connecting said block and said deflector and pivoted to each.

10. The structure of claim 9 characterized by the provision of means for limiting the rotation of said deflector about its pivotal connection with the link.

11. The structure of claim 9 characterized by the provision of means for limiting the rotation of said link about its pivotal connection with the block.

12. The structure of claim 9 characterized by the provision of means for lifting said link, and, with it, the deflector member, during the retracting excursion of the deflector member.

13. The structure of claim 9 characterized by the provision of means for causing rotation of said block in relation to said arm, in response to rotation of said arm.

14. The structure of claim 9 characterized by the employment of a member mounted for sliding movement along said arm, a linkage connecting said slidable member with the block, and means for moving said slidable member along said arm in response to rotation of said arm.

15. The structure of claim 9 characterized by the employment of a member mounted for sliding movement along said arm, a linkage

connecting said slidable member with the block, and means for moving said slidable member along said arm in response to rotation of said arm, including a cam mounted in the line of movement of said arm and a cam engaging member associated with said slid- able member.

16. The structure of claim 9 characterized by the employment of a member mounted for 10 sliding movement along said arm, a linkage connecting said slidable member with the block, and means for moving said slidable member along said arm in response to rotation of said arm, including a plurality of cam 15 elements mounted in the line of movement of said arm, and a plurality of cam engaging members associated with said slidable member and adapted for successive engagement with the opposed cam elements.

20 17. For use with a car unloader including a tiltable cradle and means for positioning a car thereupon, a deflector member, and means for inserting said deflector member into and retracting it from said car, includ- 25 ing an arm in pivotal relation with said deflector member and means for rotating it, and means for rotating the deflector member in relation to said arm, including a member mounted for slidable movement along said 30 arm, a linkage connecting said slidable mem- ber with the deflector member, and means for moving said slidable member along said arm, in response to rotation of the arm.

35 18. The structure of claim 17 characterized by the employment of a cam element mounted in the line of movement of said arm and an opposed cam engaging member associated with the slidable member.

40 19. The structure of claim 17 character- ized by the employment of a plurality of cam elements mounted in the line of movement of said arm, and a plurality of opposed cam en- 45 gaging members associated with the slidable member and adapted for successive engage- ment with said cam elements.

50 20. The structure of claim 17 characterized by the employment of a plurality of cam ele- ments mounted in the line of movement of said arm, and a plurality of opposed cam en- 55 gaging members associated with the slidable member and adapted for successive engage- ment with said cam elements, said cam ele- ments being positioned at varying distances from the center of rotation of the arm.

60 21. For use with a car unloader including a tiltable cradle and means for positioning a car thereupon, a deflector member and means for inserting it into and retracting it from said car, said means including a generally vertical 65 shaft, an arm mounted upon the upper end of said shaft, a block pivoted to the end of said arm, means for rotating said block in response to rotation of said arm, a deflector member, a link connecting said deflector member and said block and pivoted to each, sheaves on

said block, sheaves on said arm, a cable con- nection, with said link, passing about said sheaves and downwardly along said shaft, a motor adapted to rotate said shaft, and a drum associated with said motor, a cable being secured to said drum, a sheave about which said last mentioned cable passes, a weight as- 70 sociated with said cable, and a connection be- 75 tween said first mentioned cable and said sheave.

22. The structure of claim 21 characterized by the employment of a relatively small weight upon said last mentioned cable, of a weight insufficient to overcome the weight of said link and deflector member and a large weight, in the line of upward movement of said small weight, of a weight sufficient to 80 overcome the weight of link and deflector and to cause their upward movement in response to the reeling in of said last mentioned cable 85 about said drum.

23. For use with a car unloader including a tiltable cradle and means for positioning a car thereupon, a deflector member and means for inserting it into and retracting it from said car, said means including a generally vertical shaft, an arm mounted upon the upper end of said shaft, a deflector member in pivotal connection with the end of said arm and means for rotating said deflector member, about said pivotal connection, in response to rotation of the arm, a cable in connection with said deflector member, a motor adapted to rotate said shaft, a drum associated with said motor, a cable secured to the drum, a sheave about which said last mentioned cable passes, a weight associated with said last mentioned cable, and a connection between said first mentioned cable and said sheave.

24. The structure of claim 23 character- 100 ized by the provision that the first mentioned cable extends from the deflector member to the vertical shaft and downwardly through 105 said shaft.

25. For use with a car unloader including a longitudinally tiltable cradle and means for positioning a car thereupon, a deflector member and means for inserting said deflector member into and retracting it from said car, including a generally horizontal arm, the deflector member being mounted upon one end of said arm for rotation therewith, means for rotating said arm to insert or 115 retract said deflector and means, operative to raise or lower said deflector at a predeter- 120 mined point in its excursion of insertion or retraction.

26. For use with a car unloader including a laterally tiltable support and means for securing a car thereupon, a deflector mem- 125 ber adapted to be positioned generally hori- zontally along the side of the support and laterally out of line with the car door when 130

in inoperative position, means for inserting said deflector into and retracting it from the interior of said car, and means for moving said deflector vertically during its movement into and out of operative position, and for tilting it in a generally vertical plane, during its movement into and out of the car.

27. For use with a car unloader including a longitudinally tilttable cradle and a car support laterally tilttable in relation to said cradle, and means for positioning a car thereupon, a deflector member associated with the longitudinally tilttable cradle, and means for inserting it into and retracting it from the car, including an arm upon which said deflector member is mounted, a shaft to which said arm is fixed and means for rotating said shaft.

Signed at Chicago, county of Cook and State of Illinois, this 23rd day of September, 1929.

ELWIN H. KIDDER.
